UNITED STATES PATENT OFFICE.

LEON D. OBERT, OF UNDERWOOD, MINNESOTA.

GRAIN SEPARATOR.

Application filed June 2, 1923. Serial No. 643,043.

To all whom it may concern:

Be it known that I, LEON D. OBERT, a citizen of the United States of America, residing at Underwood, in the county of Otter Tail and State of Minnesota, have invented certain new and useful Improvements in Grain Separators; and I do hereby declare that the following is a full, clear, concise, and exact description of the invention, such as will enable others skilled in the art to which it appertains to make and use the same.

This invention relates to improvements in grain separators, having for an object to provide a rotary grain separator, especially advantageous for use in separating wheat and like grains from oats, wheat seeds, sand and dirt, and delivering the grain so separated by discharge means into a suitable receptacle.

It is also an object of the invention to provide a rotary grain separator employing a novel form of rotatable separator cylinder having internal means for receiving and removing the grains of wheat from the bulk of matter discharged thereinto for separation and conveying the same away from such bulk and discharging it at a predetermined point of its rotary path of travel into a discharge way leading from the separator.

It is a further aim of the invention to provide a rotary separator wherein means are utilized for agitating the matter discharged thereinto for separation in order that the same will be evenly distributed throughout the separator cylinder and the lighter grain, such as oats and other matter caused to pass therefrom, thus leaving only heavier matter for separation by the cylinder.

Other objects will be in part obvious and in part pointed out hereinafter.

In order that the invention and its mode of operation may be readily understood by persons skilled in the art, I have in the accompanying illustrative drawings, and in the detailed following description based thereon, set out one possible embodiment of the same.

In these drawings:

Figure 1 is a side elevation of the improved rotary grain separator;

Figure 2 is a vertical longitudinal section through the separator;

Figure 3 is a vertical transverse section taken on the line 3-3 of Figure 1 looking in the direction in which the arrow points; 55

Figure 4 is an enlarged vertical transverse section taken on the line 4-4 of the Figure 1 looking in the direction in which the arrow points; and, 60

Figure 5 is an enlarged fragmentary detail in section showing the manner in which the wheat receiving and conveying pockets are formed in the internal face of the cylindrical separator shell. 65

Having more particular reference to the drawings, in connection with which like characters of reference will designate corresponding parts throughout, the improved separator may be stated to comprise a cylindrical separator shell indicated in its entirety by the numeral 1 and hereinafter referred to for convenience as the "separator cylinder", such separator cylinder being mounted for rotary movement in a horizontal plane 75 upon roller bearings 2 rotatably mounted in the bearing bracket provided therefor by means of standards generally indicated by the numeral 3, such roller bearings, as shown in the Figure 1, being engaged in circumferentially disposed rings or circular tracks 4 disposed about the opposite end portions of the separator cylinder; preferably four of these roller bearings 2 with their respective standards 3 being employed and arranged 80 upon the opposite sides and adjacent the opposite ends of the separator cylinder. 85

In order that rotary motion may be transmitted to the separator cylinder, a gear ring 5 is arranged about the intermediate portion of such cylinder and is adapted to have the teeth thereof mesh with a driving pinion 6 mounted upon the inner end of a longitudinally disposed shaft 7 mounted in bearings 8 beneath the separator cylinder 1; a frictional gear being carried upon the outer end of the shaft 7 and receiving belt gearing 9 thereabout for a purpose which will be hereinafter more fully described, while suitable driving means, not shown, is connected to 100 the frictional gear or to the shaft 7. In this connection, it is to be understood that the driving means, not shown, may be provided with variable feed power transmitting mechanism or various other forms of mechanical devices, common in the art, in order 105

that the separator cylinder may be selectively rotated at that speed most efficient to its separation operation.

The inner or internal face of the separator cylinder 1 has a plurality of sets of pockets generally indicated by the numerals 10 and 11 formed therein, such sets or groups of pockets each covering approximately one-half of the internal area of the cylinder and extending to its intermediate portion from its opposite end as clearly shown in the Figure 2; such groups of pockets being of different sizes, whereby, as illustration, the pockets 10 will serve to receive wheat seed, sand and dirt from the bulk of matter discharged into the separator for separation, while the pockets 11 are of sizes sufficient to receive the larger wheat grains or other grains to be separated from such bulk.

Disposed longitudinally of and extending through the lower portion of the separator cylinder 1 is a shaft 12 having a plurality or series of radially disposed agitating blades 13 fixedly mounted thereon, the opposite ends of the shaft 12 being received in suitable bearings 14 positioned externally of and adjacent the opposite ends of the separator cylinder, one end of the shaft 12 having a frictional gear thereon adapted to receive the belt gearing 9 thereabout in order that rotary motion may be transmitted to the agitating arms or blades 13 from the shaft 7.

With a view towards providing means for causing the discharge of matter to be separated into the separator cylinder 1, a discharge chute 15 is mounted upon a supporting structure generally indicated by the numeral 16 and, as shown in the Figures 1 and 2, is inclined downwardly and extends into one end of the rotatable separator cylinder adjacent those groups of openings indicated by the numeral 10. Thus, the bulk of matter to be separated, when discharged into the separator cylinder will first be engaged with the smaller group of pockets 10 and in consequence, the smaller material such as wheat seed, dirt, sand, et cetera will be received in said pockets, whereas the larger particles of the matter, namely, the wheat kernels will be caused to pass over said smaller group of openings until the same reach and are received in the larger group of openings or pockets 11.

Oppositely disposed inclined discharge chutes 17 and 18 are arranged longitudinally and internally of the upper portion of the separator cylinder 1, their inner ends being at a point adjacent the meeting of the several groups of pockets 10 and 11, while the outer portions thereof are supported upon the structures indicated by the numeral 16 and 18, this latter supporting structure also serving as a supporting means for a down-

wardly inclined discharged chute 19 extending to a point adjacent and communicating with the opposite ends of the separator cylinder 1 in order that the lighter grains and matter, such as wild oats and the like, may be conveyed from the separator cylinder during its rotation.

The operation of my improved grain separator may be reviewed as follows:

The separator cylinder 1 is rotated at the desired speed or velocity by means of the driving shaft 7 having its pinion 6 meshing with the ring gear 5 disposed about the intermediate portion of the separator drum periphery, such cylinder being supported in its rotary movement upon the various roller bearings 2 carried in the upper ends of their respective standards 3. Matter to be separated is placed upon the chute 15 and caused to discharge into that end of the separator cylinder communicating therewith. The matter to be separated upon contacting with the internal face of the cylinder will be distributed thereover by means of the radially disposed agitator blades or arm 13, the smaller particles, grains, or seeds passing into the smaller group of pockets 10, while the larger grains, such as wheat or the like, are advanced over the smaller group of pockets 10 and caused to move onto that internal area of the separator cylinder 1 provided with the larger group of pockets 11. At this time, the larger grains, namely the wheat kernels, are received in the pockets 11. Because of the rotary movement of the separator cylinder 1, the smaller grains, seeds, dirt or sand and the wheat kernels will be carried in the groups of pockets 10 and 11 respectively, until they drop by gravity from such pockets into the receiving chute therefor, the smaller particles, such as seeds, dirt or sand passing from the pockets 10 into the discharge chute 17, while the grains of wheat are discharged from the larger group of pockets 11 into the discharge chute 18. From these several chutes, the matter so separated may be delivered into suitable receptacles, not shown. The lighter material from the bulk of matter discharged for separation into the separator cylinder will, because of its lighter weight, work upwardly and by reason of the constantly rotating agitator arms 13, will be advanced longitudinally through the separator cylinder and discharged from its opposite end into the inclined chute 19. These lighter particles, as will be understood, may be in form of chaff, wild oats, et cetera.

Manifestly, the construction shown is capable of considerable modification and such modification as is within the scope of my claims, I consider within the spirit of my invention.

I claim:

1. A rotary separator comprising a rota-

table separator cylinder having groups of pockets of different size formed upon its internal face, oppositely inclined chutes extending through and arranged adjacent the upper portion of said cylinder for receiving and discharging matter delivered thereto from said groups of pockets from the cylinder, agitating means arranged in said separator cylinder in proximity to its lower portion, a delivery chute extending into one end of the cylinder adjacent the smaller group of pockets, and a discharge chute extending from the opposite end of said cylinder adjacent the larger group of pockets.

2. A rotary separator comprising a rotatable separator cylinder having groups of pockets of different size formed upon its internal face, oppositely inclined chutes extending longitudinally of and arranged in the upper portion of said cylinder for receiving and discharging matter delivered thereto from said groups of pockets from

the cylinder, a shaft mounted in bearings and extending longitudinally through the lower portion of said cylinder, a plurality of agitating means carried on said shaft, a common means for imparting rotary motion to said cylinder and shaft, oppositely inclined chutes extending longitudinally through the upper portion of said cylinder having their adjacent ends meeting at a point adjacent the meeting of the several groups of pockets in the internal face of the cylinder for receiving and discharging matter delivered thereto from said groups of pockets from the cylinder, a delivery chute extending into one end of the cylinder adjacent the smaller group of pockets and a discharge chute extending from the opposite end of the cylinder adjacent the larger group of pockets.

In witness whereof I have hereunto set my hand.

LEON D. OBERT.
